DAVID W. CHURCH, OF SAN DIEGO, CALIFORNIA, ASSIGNOR, BY MESNE ASSIGNMENTS,
TO RUDOLPH A. DALLUGGE, OF LOS ANGELES, CALIFORNIA.

ORE CRUSHING AND AMALGAMATING MILL.

1,266,406.

Specification of Letters Patent. Patented May 14, 1918.

Application filed November 22, 1916. Serial No. 132,789.

To all whom it may concern:

Be it known that I, DAVID W. CHURCH, a citizen of the United States of America, residing at San Diego, in the county of San Diego and State of California, have invented a new and useful Ore Crushing and Amalgamating Mill, of which the following is a specification.

This invention relates to an improvement 10 on the type of ore crushing and amalgamating mill disclosed in the United States patent to Wiswell No. 307,513, dated Nov. 4, 1884, in which the crushing and grinding rolls are provided with inclined inner and 15 outer faces which roll on the inclined walls of an annular trough. Such mills have been found subject to serious objections, which have heretofore prevented their successful use. One of the objectionable features in 20 the operation of a mill of the Wiswell type is that the mercury used for amalgamation quickly becomes floured by the grinding action of the rolls, which, in said mill, work down into the bottom of the trough formed 25 by the inclined walls of the bed or die, so as engage the mercury therein and grind it with the ore and water. Furthermore the said rolls, working more or less closely in contact with both inner and outer walls of 30 the trough, cause excessive displacement and agitation of the pulp or mixture of ground ore and water, in such manner that a portion of the material is liable to be splashed over the outlet or overflow before it is thor- 35oughly ground and deprived of its values.

The main object of the present invention is to provide a crushing and amalgamating mill in which the rolls will be held clear of the mercury or quicksilver so as to avoid 40 flouting of the latter. Another object of the invention is to retain the rolls in contact with or effectively adjacent to the inner inclined wall of the trough of the mill, and sufficiently separated from the other inclined 45 farther wall thereof to permit flow of the pulp between the rolls and the farther wall, thereby preventing undue displacement and agitation.

The accompanying drawings illustrate 50 embodiments of my invention, and referring thereto:

Figure 1 is a plan view of the mill, partly in section.

Fig. 2 is a vertical section thereof.

55 The mill comprises a bed or die 1, formed

with an annular trough 2, having inclined inner and outer walls 3 and 4, so that the trough is V-shaped in cross section. Suitable means, not shown are provided for feeding ore and water to one side of said trough and suitable outlet or overflow means 5, provided with screens 6 may be provided for discharging the waste pulp at the other side of the mill. Rolls or wheels 7 are mounted to run on the inner wall or face 60 of the trough 2, said rolls being fast on the respective shafts 8 which are mounted to revolve with a vertical central post or shaft 9. Said shaft 9 is mounted to turn in suitable bearings and is provided with means 65 such as gears 10 and 11 for driving the same. A frame 13 on shaft 9 carries vertical guides 14 for bearing blocks 15 in which the respective shafts 8 are journaled. Said shafts 8 are mounted loosely at their inner ends 70 in sockets 17 in a member 19 on shaft 9, so that the wheels or rolls 7 may rise and fall somewhat as required by the crushing operation on the material in the trough 2, springs 20 serving, however, to press the blocks 15 75 down so as to tend to hold the rolls 7 in contact with the inner face or wall 3 of the annular trough or with the ore material thereon. Radial movement of the shafts 8 and of the rolls 7 carried thereby is however 80 prevented or limited by means on said shafts 8 engaging with blocks 15, said means consisting, for example, of anti-friction washers 22 engaging with said blocks and a set collar 23 fastened on shaft 8 by set screws 24 or 85 otherwise. The shafts 8 are thereby held from outward movement in such manner that the rolls or wheels 7 carried thereby are retained in contact with or positioned adjacent to the inner inclined wall of trough 95 2, so that the lower edge or periphery of the roll is not permitted to work down into the lowermost part of the trough containing the quicksilver, indicated at 28, but is held clear thereof and also separated from the 100 outer wall or face of the trough. Frame 13 is preferably mounted to slide vertically on shaft 9, being connected thereto by a spline connection 13'.

If necessary in any particular case, brace 105 rods 30 may be connected to the blocks 15 and to the central member 19, in such manner as to hold the blocks from bearing too hard on the vertical guides 14, and to thereby insure easy vertical movement of the rolls. 110

The vertically movable bearing blocks 15 and the brace means therefor, hold the shafts 8 and the rolls carried thereby inwardly toward the axis of rotation of the carrier, 5 without interfering with the vertical motion of the rolls. Blocks 15 may have lateral flanges 15' engaging the inner faces of guides 14 to take radial pressure.

In the operation of the mill, the rotation 10 of central shaft 9 causes rolls 7 to run around on the inner wall or face of the trough 2, the lowermost part of the rolls being always above the level of the quicksilver in the trough and the outer face of 15 the roll being always spaced from the outer wall 4 of the trough. The relative position of the roll and trough faces at the front of each roll is such that the ore material is crowded between the inner inclined face of 20 the roll and the inner wall 3 of the trough, and by holding the roll toward or in contact with such inner wall, the ore is effectively crushed and ground between the roll and wall or die face, and the circulation of the 25 pulp by the action of the roll eventually brings the values in contact with the body of quicksilver in the bottom of the trough 2, so that amalgamation is produced without direct contact of the roll with the quicksilver, thereby avoiding flouring of the 30 quicksilver due to grinding of the latter in with the pulp. Sufficient space is left between the rolls and the outer wall 4 of the trough to enable the pulp to flow back at 35 the outside of the rolls, as the rolls advance or plow through the pulp, thereby avoiding piling up of the pulp in front of the rolls in such manner as to cause undue displacement and agitation thereof and resulting 40 splashing of incompletely ground pulp over the outlet lip or overflow. The motion of the rolls 7 over the inner face of the trough 2 is such as to scour and brighten

the gold and thereby make amalgamation possible on rusty gold.

The rolls are arranged around the shaft so that the pressures required for holding the rolls against the inclined inner wall of the trough balance one another and there is no lateral pressure on the shaft.

What I claim is:

1. An ore crushing, grinding and amalgamating mill comprising an annular trough adapted to contain a body of quicksilver and having an inclined inner wall, a shaft 55 mounted to rotate on a vertical axis coaxial with said annular trough, and a roll mounted to revolve with said shaft and to have freedom of vertical movement, and supported to run only on the inclined inner 60 wall of the trough, above the bottom of said trough and away from the outer wall thereof.

2. An ore crushing, grinding and amalgamating mill comprising an annular trough 65 adapted to contain a body of quicksilver and having an inclined inner wall, a shaft mounted to rotate on a vertical axis coaxial with said annular trough and a plurality of rolls arranged around said axis and mounted 70 to revolve with said shaft and to run only on the inclined inner wall of the trough above the bottom of said trough and away from the outer wall thereof, the mounting 75 of said rolls providing for independent vertical movement thereof, but holding the rolls against said inner wall, in such manner that the radial stresses due to the several rolls are balanced with respect to the shaft and there is no resulting lateral pressure 80 on the shaft.

In testimony whereof I have hereunto set my hand, at Barstow, California, this 13 day of November, 1916.

DAVID W. CHURCH.
